tion of New York

Application December 21, 1935, Serial No. 55,517

12 Claims. (Cl. 109—1)

This invention relates to cash protecting counters, tills, etc., such, for instance, as are suitable for use by tellers in banks, cashiers in stores, and in ticket offices, and in many other environments.

5 A principal object of this invention is to provide a device which normally houses money, or other articles, for convenient access and handling by the teller, cashier, or other attendant, and which may be caused instantly to transfer the
10 money or other articles to an inaccessible safeguarded location and thus prevent loss of the money or other articles by robbery in the event of a hold-up, or other emergency, and to provide a device of the character referred to and which
15 conserves and economizes space, which is simple and requires little effort to manipulate for the transaction of business, and which is provided with means controllable at one or more remote or near points, or both, as desired, for safeguarding the contents positively and instantly, and to provide safeguarding means which effectively prevent unauthorized access to the contents when transferred to safeguarded location, and a further object of this invention is to provide a device
20 of the character described and one which operates quietly, smoothly and without vibration or pounding, and is attractive in appearance.

25 A further object of this invention is to provide a device of the character described, and one that is sturdy and durable and not apt to get out of order.

30 Other objects of this invention will be in part obvious and in part pointed out hereinafter.

In accordance with this invention a burglar-35 proof chest is equipped with a front closure or frame that is pivoted at its bottom to rock on a horizontal axis, the closure toward its top carrying a money tray which swings out of and into the chest as the closure is pivotally opened there-
40 from and closed thereto. The tray is provided with means whereby a person at a near or remote point, or at either point, may cause the contents of the tray to fall therefrom into the bottom of the chest and a burglar-proof shield
45 to be interposed above the transferred tray contents, irrespective of the pivotal positions of the closure and tray, and means are provided for preventing access to the contents so protected except by authorized means, such, for instance,
50 as requires the unlocking of a burglar-proof lock, which if desired may be a time lock. By pivotal-
55 ly mounting the money tray to swing into and out of the chest, not only the space within the chest but also the space required for opening the counter and for handling articles therein is con-

served and economized. Various operating means, safety means, and other means and features are provided as will appear more fully as the description proceeds.

5 In order that a clearer understanding of this invention may be had, attention is hereby directed to the accompanying drawings, forming a part of this application, and illustrating certain possible embodiments of this invention, and in which:—

10 Fig. 1 is a front elevation of a counter cash protector embodying this invention, certain hidden parts being indicated by dash lines;

15 Fig. 2 is a side elevation of the protector, open to normal extent;

20 Fig. 3 is a vertical sectional view of the pro-
tector, closed, and is taken on the line 3—3 of Fig. 1;

25 Fig. 4 is a horizontal sectional view of the de-
vice, and is taken on the line 4—4 of Fig. 3, cer-
tain parts being shown broken away to expose
certain units of the construction;

30 Fig. 5 is a rear view of a part of the construc-
tion, and is taken on the inclined line 5—5 of Fig. 3;

35 Fig. 6 is a fragmentary horizontal sectional
view of the device, and is taken on the line 6—6
of Fig. 3, the safeguarding protective closure being
shown closed;

40 Fig. 7 is a fragmentary isometric view of a de-
tail of the restraining means for the money com-
partment bottom releasing means; and

45 Fig. 8 is a fragmentary isometric view of one
of the protective closure stop and latch blocks
and a fragment of the latch.

50 Similar reference characters refer to similar
parts throughout the several views of the draw-
ings.

55 Referring to the drawings, there is a burglar-
proof chest 10, having an open front provided
with a closure comprising a frame 11 hinged,
along its bottom, as at 12, to the chest and hav-
ing a door opening fitted with a door 13 hinged,
along one side, as at 14, to one side of the frame
11. Fixed to the frame adjacent each side edge
15 is an inwardly extending side plate, 15 and 16,
strips 15' and 16' inwardly therefrom and se-
cured thereto, and upright cross-partition mem-
bers 17, 18, 19, 20, 21, and 22 extend be-
tween and are secured to these strips, forming
three compartments 23, 24 and 25. A plate 26
hinged, as at 27, to wall 17 constitutes the bot-
tom of compartment 23; a plate 28 hinged as at
29, to wall 19 is the bottom of compartment 24;
and a plate 30 hinged, as at 31, to wall 22 is the

bottom of compartment 25. Any or all of the compartments may be further divided by additional partition plates, such as 32, secured to the walls, into spaces suitable to receive and house 5 stacks of bills. As shown, compartment 25 is not so divided.

To maintain the bottoms 26, 28, and 30 elevated and in article supporting position, a bar 33 is slidably held in brackets 34 secured to side plate 10 16, and has studs 35, 36, and 31, each pivotally carrying a dog 38, 39, and 40, held upright against stop pins 41, 42, and 43, therefor, by tension springs 44, 45, and 46 extended between pins 47, 43, and 48 on the bar and the tails 49, 50, and 15 51 of the dogs. Dog 38 has a finger 38' normally seating under a pin 52 extending outside of the side edge of bottom 26 from a bracket 53 secured thereto at its free edge; dog 39 has a finger 39' normally seating under a pin 54 extending outside of the side edge of bottom 28 from a bracket 20 55 secured thereto at its free edge, and dog 40 has a finger 40' normally seating under a pin 56 extending outside of the side edge of bottom 30 from a bracket 57 secured thereto at its free edge. Preferably this arrangement is repeated at the other sides of the bottoms 26, 28, and 30 to give the bottoms better support, the sliding bar 58, corresponding to bar 33, being mounted on the opposite side plate 15.

Means are provided for moving the bars 33 and 58 rearwardly to slide the dog fingers from under the pins so that the bottoms will swing down by gravity and dump the contents of the compartments into the space beneath them. If desired, 30 suitable checks 59, 60, and 61, which may be pneumatic, or of any other suitable type, are connected with the bottoms 26, 28, and 30, to silence and ease their fall, without, of course, preventing them from opening, when released from the dogs, and dumping the contents of the compartments. Any 35 suitable means may be provided for shifting the bars 33 and 58 to release the bottoms, and such means may be either manual, mechanical, electrical, or otherwise, as desired. Electrical means are illustrated, and such as may be controlled from one or more remote points or from a near point, or both, as desired.

A back plate 62 extends between and is secured to the side plates 15 and 16 at the upper portions 50 of their rear edges and extends part way down. A shaft 63 is journaled in suitable bearings 64 secured to the rear of plate 62. Fixed to each end of shaft 63 is a finger plate, one of which, 65, seats in a notch 66 provided therefor in slide bar 55 33, the other plate, 67, seating in a similar notch in the opposite slide bar 58. An arm 68 is fixed to shaft 63 near its center, and a spring 69 coiled about the shaft and having one end 70 bearing against plate 62 and the other end 71 bearing 60 against arm 68 continuously urges shaft 63 to rotate to slide the bars 33 and 58 rearwardly and release the money compartment bottoms. However, such rotation of shaft 63 is normally prevented by a pin or stud 72 on arm 68 being engaged by a beveled stop shoulder 73 on one end 65 of a detent lever 74 pivoted on a pin or stud 75 secured to plate 62 and having its opposite end pivotally connected with the armature 76 of a solenoid 77, mounted on a bracket 78 secured to plate 62 and normally energized to hold its armature retracted and preventing stud 72 from camming beveled stop 73 away and passing by, which the stud 72 will do as soon as solenoid 77 is de-energized and ceases to resist such movement of lever 74; and the accompanying movement of

shaft 63 will retract slide bars 33 and 58 and cause the dumping of the contents of the money compartments 23, 24 and 25.

The solenoid 77 may be de-energized to cause dumping of the contents of the money compartments by one or more suitable circuit breakers (not shown), at near or remote points, and either manually operable, or otherwise, and properly included in the solenoid circuit. If such circuit breakers are of the push button type, the circuit 10 may also be arranged to be broken by arm 63 when it moves upon being released. This will conserve consumption of power. As shown, secured to plate 62 is a switch block 80 receiving the cable 81 having two conductors, one, 82, connected with 15 a stationary contact finger 83 on the block and the other, 84, connected to a resilient contact finger 85 mounted on the block and normally held against contact 83 by a set screw 86 carried on a bracket 87 fixed to arm 68, and so arranged that 20 when arm 68 moves from normal position spring contact 85 will separate from contact 83 and break the solenoid circuit in which the conductors are included. A block 88 is secured to plate 62, power cable 89 leading thereto, cable 84 leading 25 therefrom as well as cable 90 leading to solenoid 77, and at which the several conductors are connected.

Preferably a stop bracket 91 having a bumper 92 is positioned on plate 62 to be engaged by and 30 to limit outward swinging of arm 68. To lessen the shock of arm 68 against the bumper, arm 68 may be overlapped by a spring finger plate 93 secured to block 80.

The mechanism and circuit are reset from the 35 emergency to normal condition by means of a hand lever 95, pivoted on a pin or stud 96 secured to plate 16, and having an end 97 seating in a notch 98 in bar 33, and may be moved manually to move the bar 33 back to normal position, and 40 consequently will move the bar 58 and arm 68 also back to normal positions, whereupon the contacts 83 and 85 will come together and close the circuit to solenoid 77, and stud 72 of arm 68 will seat behind and become locked by the nose 73 of lever 45 74, nose 73 having a beveled surface 99 so that if solenoid 77 is energized before stud 72 has passed nose 73 the stud will displace nose 73 sufficiently to pass by. The dogs 38, 39 and 40 are thus restored to normal service position. The bottoms 50 26, 28, and 30 of the money compartments 23, 24 and 25 are then lifted manually into their normal service positions, each pin 52, 54 and 56 snapping into supported position on the supporting fingers of the resiliently mounted dogs 38, 39, 55 and 40.

It will be noted that the contents of the money compartments may be dumped into the bottom of the chest irrespective of whether the rocking front and money compartment assembly is closed 60 into the chest or is open therefrom to any extent. The front frame 11, with its door 13, serves to deflect articles dumped from the money compartments when the front is open, and, if desired, suitable baffle plates 100 and 101 may be affixed to 65 the door 13 to prevent any dumped articles from becoming caught on the lock case 102 or other parts on the rear of the door or frame.

To prevent access to the articles dumped to the bottom of the chest, a sliding, two-piece telescopic cover is provided to slide just under the lower edge of back plate 62, on tracks 103 secured to the side plates 15 and 16, the cover comprising a lower plate 104 having a contact strip 105 on its forward edge, and an upper plate 106 having 70

6 a pick up strip 107 under its rear edge. A standard door closer, 108, is hung on a bracket 109 secured to a bar 110 extending between and fastened to the under surfaces of the tracks 103 on plates 15 and 16, and its pusher arm 111 is pivotally connected to an angle bracket 112 secured on the top of upper closure plate 106.

10 The closure plates 104 and 106 are normally held latched in telescoped relation at the rear ends of tracks 103 by the nose 113 of a latch lever 114 pivoted on a pin or stud 115 carried on a bracket 116 mounted on the rear of plate 62, the heel 117 of lever 114 being normally abutted by one arm 118 of a bell crank lever pivoted, as at 15 119, on bracket 116 and being held in such position by spring 120. The other arm 121 of the bell crank lever is engaged by a plunger pin 122 slidably mounted in block 123 secured to plate 62 and having a head 124 protruding from the opposite 20 side of plate 62 in position to be engaged and depressed by the bottom 30 of money compartment 25 when it falls, thus pivoting the arm 118 of the bell crank lever out of engagement with heel 117 of lever 114, and releasing the closure plate 106 25 to be pushed forward by the door closer 108. During this forward movement of plate 106, its strip 107 will engage the strip 105 of the lower plate 104, and both plates, thus extended will be moved by the door closer to the forward end of 30 the tracks 103 and will completely close the space between the front frame and door and the rear plate 62, thus preventing access to articles in the bottom of the chest beneath the closure. Preferably when the plate 106 reaches the front ends 35 of tracks 103 it becomes latched at each end by spring finger latches 125 mounted on plate 106 and which engage stop blocks 126 secured to the tracks to prevent the plates from being pried back against the force of the closer 108. Latches 40 125 are only accessible from below the closure plate so that to release the plates it is necessary to open the chest door 13, which is preferably provided with a burglar-proof lock (in case 102) and bolts 127, 128 and 129 engaging the frame 11.

45 To restore the closure plates 104 and 106 from this emergency to normal position, the bottom 30 of money compartment 25 is reset into normal position, the latches 125 disengaged from plate 106 and then this plate is pushed back until the 50 nose 113 snaps in front of the plate, which it will do because of compression spring 130 pressing against lever 114, and the arm 118 of the bell crank lever will snap into abutting engagement with heel 123 of lever 114, and thus the closure is 55 held retracted until the plunger 122 is again depressed.

The door 13 cannot be opened, however, unless the money compartment carrier is closed, since so long as this carrier is not fully closed, a nose 60 131 of a latch 132 pivoted, as at 133 to the frame 11 engages in a hole or recess 134 in the bolt 127 and prevents retraction of the bolts to unlock the door. When the compartment carrier is fully closed, a rocking lever 135, pivoted, as at 136, on 65 frame 11, and connected to latch 132 by a link 137, is engaged and so displaced by contact with a stop strip 138 on the top wall of the chest as to move and hold the latch 132 out of the bolt hole 134, thus allowing the door to be unlocked. At 70 the same time a nose 139 on lever 135 engages behind the stop strip 138 and prevents the frame 11 from being swung out. A spring 140 pulls link 137 down, but when bolt 127 is retracted, a bar 141, pivoted, as at 142, to frame 11, follows the 75 bolt down by gravity and seats under the nose

131 of latch 132 and keeps link 137 raised and nose 139 engaged behind strip 138, so that the frame 11 cannot be opened unless the bolt 127 has been shot to move aside the bar 141 and dispose its recess 134 in alignment with the latch 5 nose 131 allowing spring 140 to pull link 137 down and lower nose 139 from behind strip 138. Frame 11 may further be locked to the chest by any suitable lock, indicated by the key 143 and key cylinder 144.

10 To aid a person in swinging the chest front open, one end of a rod 150 is secured to a bracket 151 on each side plate 15 and 16 and slidably extends through a bracket 152 pivotally mounted on a stud 153 secured to the side of the chest, and 15 a compression spring 154 encircling rod 150 and compressed between brackets 151 and 152 tends to open the money compartment carrier a certain extent, for instance, so as to place compartments 23 and 24 outside of the chest. Another compression spring 155 encircling rod 150 between bracket 152 and nuts 156 on the threaded rear end of rod 150 may be provided to resiliently restrain further opening of the carrier and to bring it back to normal open position after the carrier has 25 been opened further by a person, for instance, after having had access to compartment 25. These springs also cushion movement of the compartment carrier and prevent noise and 30 pounding.

35 If desired, a spring latch 160 may be mounted on side plate 15 and adapted to snap through an aperture 161 to overlap the edge of the chest side wall to stop closing or inward movement of the compartment carrier at a normal open position, 35 but permitting further opening for access to compartment 25.

Business may be transacted very conveniently and easily with a safely protected till or cash counter having the features of this invention. 40 The cash container is counterbalanced by springs 154 and 155 so that it may be rocked with little effort to any open position or closed. The till may be held open by spring catch 160 so as to keep the money compartments 23 and 24 open 45 from the chest, affording the attendant open and convenient access thereto, yet allowing the attendant to close the till quickly and easily by pressing the catch 160 and swinging the till closed. Whenever the attendant wishes to place 50 money in the rear compartment 25, he may easily rock the till outwardly to expose this compartment, and when the till is released it will be stopped automatically by the catch 160 in the normal open position exposing compartments 23 55 and 24.

When a hold-up threatens, or at any time, the contents of all of the compartments 23, 24, and 60 25 may be dumped into the bottom of the chest instantly by anyone causing the opening of the circuit to the controlling solenoid 71, as by anyone merely pushing one of the push button circuit breakers which are understood to be included in the solenoid circuit and placed at strategic locations in the bank or other environment in which 65 the till is located. The contents are dumped to the bottom of the chest irrespective of whether the till is open or closed and irrespective of its pivotal position. Also the protecting cover or shield is closed automatically over the contents so 70 transferred to the bottom of the chest, this closure completely closing the space between the front, rear and side plates of the money compartment carrier and becoming automatically locked against displacement, and requiring opening of 75

the door 13 to secure access to the lock release to unlock the closure. Door 13 may be locked by a time lock so that this door cannot be opened by anyone until after a certain lapse of time after the time lock has been started running, and this delay is a further protection against robbers or other unauthorized persons gaining access to the protected contents of the till, since such persons would not be likely to remain while this time elapses.

The till cannot be opened unless the door 13 is closed and locked, thus making certain that the door will not strike the legs of the attendant or the floor when the till is opened and swung to and fro in use. In fact, door 13 should be kept closed and locked continuously, and, if opened to reset the protective cover to normal position, or to retrieve articles from the bottom of the chest, it should be closed and locked immediately thereafter. Unless door 13 is locked the till cannot be opened.

To reset after an emergency operation, the till is swung closed, if not already closed; door 13 is then opened and hand lever 95 is rotated to restore slide bars 33 and 58 to normal position; bottoms 26, 28, and 30 are then raised so as to become supported by dogs 38, 39, and 40 in article supporting positions; the protective closure is then unlocked and pushed back until it becomes latched by the latch lever 114, this return of the closure also resetting the door closer 108; then such of the money or other articles deposited in the safety compartment at the bottom of the chest is removed and replaced in the money changing compartments of the till, and when the door 13 is then closed, the structure has been restored to normal condition for normal use and for the transaction of business, and has been reset for the next emergency operation.

As many changes may be made in the above construction and as many apparently widely different embodiments of this invention could be made without departing from the scope thereof, it is understood that all matter contained in the above description or shown in the accompanying drawings be interpreted as illustrative and not in a limiting sense.

What I claim is:

1. A device of the character described, including, in combination, a chest, a frame pivotally mounted at its lower edge to swing on a horizontal axis from and to the chest, and a money tray carried on the upper part of said frame to swing therewith, whereby the tray is carried out of and into the chest, said frame having a door opening affording access into the chest space below the tray, and a door for said opening mounted on said frame.

2. A device of the character described, including, in combination, a chest, a money tray pivotally mounted to swing out of and into the chest, safety means connected to the tray and operable in any pivotal position of the tray to empty the contents of the tray into the bottom of the chest, and means for setting said safety means in operation.

3. A device of the character described, including, in combination, a chest, a money tray pivotally mounted to swing out of and into the chest, safety means connected to the tray and operable in any pivotal position of the tray to empty the contents of the tray into the bottom of the chest, a protective cover mounted to move into and out of protective position over articles in the bottom of the chest, means normally engaging and hold-

ing said cover out of said protective position, means for setting said safety means in operation, and means for moving said cover into said protective position, and means engaging and locking said cover in protective position.

4. A device of the character described, including, in combination, a chest having an opening in its face, a closure for said opening and including a frame having a door opening and a door therefor mounted on the frame, said frame being pivotally mounted at its lower edge to swing with its door on a horizontal axis from and to said chest to open and close said chest opening, and a money tray carried on said closure to swing therewith, whereby said tray is swung out of and into the chest through said opening, said door opening affording access to the interior of the chest when said frame is closed against the chest.

5. A device of the character described, including, in combination, a chest having an opening in its face, a closure for said opening and including a frame having a door opening and a door therefor mounted on the frame, said frame being pivotally mounted at its lower edge to swing with its door on a horizontal axis from and to said chest to open and close said chest opening, and a money tray carried on said closure to swing therewith, whereby said tray is swung out of and into the chest through said opening, door locking means engaging said door and frame for locking the door closed on said frame, closure locking means engaging said chest and frame for locking the frame closed on said chest, and means coacting with both said locking means and holding said door locking means from being unlocked unless the closure locking means are locked, and holding said closure locking means from being unlocked unless the door locking means are locked.

6. In a device of the character described, in combination, a chest having an opening, a money tray pivotally mounted to swing on a horizontal axis out of and into said chest through said opening, said tray having an article support mounted to swing on a horizontal axis into and out of article supporting position, means normally engaging and sustaining said support in article supporting position, and means for disengaging said means from said support, said support being adapted when disengaged from the sustaining means, to swing out of article supporting position to dump its contents into the chest space below.

7. A device of the character described, including, in combination, a chest having an opening, a carrier having money compartments provided with bottoms hinged to swing to open and close the compartments, said carrier being pivotally mounted on the chest to swing in said opening on a horizontal axis to move said compartments into and out of the chest, a device mounted on the carrier to swing therewith and adjustable to engage and hold said compartment bottoms closed, and adjustable to disengage said compartment bottoms for opening to dump the compartment contents, setting means mounted on the carrier to swing therewith and engaging said device, normally holding said device adjusted to hold said bottoms closed, disengaging means for adjusting said device to disengage said bottoms when released from the setting means, and operating means adapted to be actuated to disengage the setting means from the device.

8. A device of the character described, including, in combination, a chest having an opening,

a carrier having money compartments provided with bottoms hinged to swing to open and close the compartments, said carrier being pivotally mounted on the chest to swing in said opening 5 on a horizontal axis to move said compartments into and out of the chest, a device mounted on the carrier to swing therewith and adjustable thereon to engage and hold the compartment bottoms closed and adjustable to disengage said bottoms for opening, setting means mounted on 10 the carrier to swing therewith and engaging said device, normally holding said device adjusted to hold said bottoms closed, disengaging means for adjusting said device to disengage said bottoms 15 when released from the setting means, and operating means adapted to be actuated to disengage the setting means from the device, said device including a bar slidably carried on the carrier and having sustaining members engageable 20 with said bottoms.

9. A device of the character described, including, in combination, a chest having an opening, a carrier having money compartments provided with bottoms hinged to swing to open and close 25 the compartments, said carrier being pivotally mounted on the chest to swing in said opening on a horizontal axis to move said compartments into and out of the chest, a device mounted on the carrier to swing therewith and adjustable to engage, 30 and hold said compartment bottoms closed, and adjustable to disengage said compartment bottoms for opening to dump the compartment contents, setting means mounted on the carrier to swing therewith and engaging said device, 35 normally holding said device adjusted to hold said bottoms closed, disengaging means for adjusting said device to disengage said bottoms when released from the setting means, and operating means adapted to be actuated to dis- 40 engage the setting means from the device, said setting means including a solenoid-controlled latch mechanism, and said operating means including a switch controlling the solenoid circuit.

10. A device of the character described, including, in combination, a chest having an opening, a carrier having money compartments provided with bottoms hinged to swing to open and close the compartments, said carrier being pivotally mounted on the chest to swing in said opening 45 on a horizontal axis to move said compartments into and out of the chest, a device mounted on the carrier to swing therewith and adjustable to engage and hold said compartment bottoms closed, and adjustable to disengage said compartment bottoms for opening to dump the compartment contents, setting means mounted on the carrier to swing therewith and engaging said device, normally holding said device adjusted to hold said bottoms closed, disengaging means for 50 adjusting said device to disengage said bottoms when released from the setting means, and operating means adapted to be actuated to disengage the setting means from the device, a protective closure mounted on tracks secured to the carrier to swing therewith and slidable on said tracks 55

into and out of protective position over articles in the bottom of the chest, detent means engaging and holding said closure out of said protective position, closing means for sliding said closure to protective position when released from said detent, and a movable trip member for the detent means adapted to be contacted and moved by one of said compartment bottoms when swinging open to trip said detent to release said closure to be closed by said closing means.

11. A device of the character described, including, in combination, a chest having an opening, a carrier assembly including a front wall, rearwardly extending side walls, a back plate extending between said side walls, and money compartments provided by partition members extending between the side walls and bottom plates for the compartments hinged to the partition members to swing into and out of position supporting articles in said compartments, said carrier 20 assembly being pivotally mounted at its base to swing on the chest outwardly and inwardly through the chest opening, means mounted on said side plates normally engaging said bottom plates, sustaining said plates in article supporting 25 positions, and means for disengaging said means from said bottom plates to dump the contents of the compartments.

12. A device of the character described, including, in combination, a chest having an opening, a carrier assembly including a front wall, rearwardly extending side walls, a back plate extending between said side walls, and money compartments provided by partition members extending between the side walls and bottom plates for the compartments hinged to the partition members to swing into and out of position supporting articles in said compartments, said carrier assembly being pivotally mounted at its base to swing on the chest outwardly and inwardly through the chest opening, means mounted on said side plates normally engaging said bottom plates, sustaining said plates in article supporting positions, and means for disengaging said means from said bottom plates to dump the contents of the compartments, a protective telescoping cover mounted on tracks therefor secured to said side plates and extensible and slideable thereon into protective position over articles on the bottom of the chest and collapsible and slideable on the tracks 30 out of protective position, detent means carried on said back plate normally engaging and holding said cover collapsed and out of protective position, and means carried on said carrier assembly to swing therewith and engaging said closure for extending and sliding said closure into protective position when the closure is released from said detent means, and means on said back plate and adapted to be operated by one of said compartment bottoms when said bottom 35 moves out of article supporting position to engage and trip said detent means to release said closure for extension and movement into protective position by said closing means.
